UNITED STATES PATENT OFFICE

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND

ATTACHMENT HOOK FOR SAFETY BELTS

Application filed May 8, 1930. Serial No. 450,664.

My invention relates to improvements in means provided in buildings adjacent the window frames thereof for the attachment of the ends of safety belts used by window cleaners, and more particularly, to the provision of hooks which are built into the window frames in the course of production so that the same will be in position when the frames are installed.

10 It is an object of my invention to provide a window frame or casing with attachment hooks which are loosely built into the same, and whose projecting knobs or heads may be moved within the confines of the window frames or casing so as to economize space and permit of a greater number of frames or casings being packed in a freight car for shipment.

20 It is another object of my invention to provide a window cleaner's hook secured to the window frame in such a manner that the strong and rigid window frame or casing is utilized to take all the stress to which the hook is ordinarily subjected.

25 Other objects will in part be obvious and in part be pointed out hereinafter.

To the attainment of the aforesaid objects and ends, my invention consists in the novel features of construction, and in the combination, connection, and arrangement of parts hereinafter described and then pointed out in the claims.

In the accompanying drawings forming part of this specification, wherein like numerals of reference indicate like parts, —

35 Figure 1 is a front view partly broken away showing a metal window frame or casing with a pair of attaching hooks applied thereto constructed according to and embodying my invention;

40 Fig. 2 is an enlarged detail transverse section on the line 2—2 of Fig. 1;

45 Fig. 3 is an enlarged detail front view showing a portion of a window frame or casing with a hook secured thereto;

Fig. 4 is an enlarged detail perspective view of a hook detached from its support;

50 Fig. 5 is an enlarged detail front view, similar to Fig. 3, showing a double hook;

Fig. 6 is an enlarged detail end view of a

portion of a window frame or casing with a modified form of hook secured thereto;

Fig. 7 is a transverse section on the line 7—7 of Fig. 6 showing the hook adjusted to its inoperative position for shipment, and

Fig. 8 is a view similar to Fig. 7, showing the hook adjusted to operative position.

In the drawings 10 designates a metal window frame or casing of well-known construction, comprising hollow jambs, or side-members 11, and sill 12. Within the jambs 11 work the sliding sashes 13, of which only the lower one is shown.

14 denotes attachment hooks to receive the opposite ends of a strap or other flexible member movably secured to the belt which is usually worn by window cleaners when working upon the outside of a window. Each jamb or side member 11 is provided in its outwardly projecting portion 11^a, about midway of its height with a right-angular horizontal slot 15 which is arranged partly in the outer side of the projecting portion 11^a, and partly in the side wall thereof.

Each hook 14 comprises a substantially flat base 16 having a slightly raised central portion 17 whose outline corresponds to that portion of the slot 15 disposed in the side walls of the projecting portion 11^a of the frame or casing 10, and from one edge of said base 16 extends an angular shank 18 having a head 19 projecting normally beyond the front wall 11^a after the window frame has been built into the building and enclosed by masonry 20.

The medial portion of the hook is substantially square in cross section so as to permit of the hook being inserted in the slot 15 of the frame, and it has its inner side cut away at 21, at right angles to the normal of the base 16, to form a bearing surface adapted to bear against the outer wall 11^a of the frame member 11, when the hook 14 is adjusted to its projected operative position, as shown at Figs. 1, 2 and 3, and secured to such position by washer 22 and screw 23 which extends into the raised central portion 17 of the base 16, and has its head 23^a and washer 22 extending partly beyond the edges of the shank 18 en-

gaging the side wall of the projecting portion 11^a of the frame or casing 10.

In assembling the parts of the window frame or casing 10, the hooks 14 are each applied thereto by passing the head 19 and shank 18 through the slot 15 in the side member 11 from within the same, and then adjusting the hook to the position shown in broken lines at Fig. 3, for shipment, in which position the hook 14 lies wholly within the geometrical outlines of the frame or casing 10.

When the window frame is properly positioned within the opening in the wall of a building during the process of construction, the hooks 14 are then swung outwardly, as illustrated in full lines at Fig. 2, and secured in place in the side member 11 by the screws 23 and washers 22, and the masonry 20 thence completed about the same. When the hook 14 is thus secured in position the entire outer surface of the base 16 will find a bearing against the interior side of the frame member 11, which latter, being made of metal, will afford the necessary support therefor and withstand all strains to which the hook may be subjected in the course of ordinary use.

In Figure 5, I have shown a modification of my invention, wherein two hooks 14^a in close proximity are mounted upon a single base 16^a and secured within the frame by a screw 23^a. This double hook arrangement affords an increased support or attachment for such belts as are provided at their ends of their supporting strap with attaching devices having elongated openings, or double rings or eyes therein to give the window cleaner greater security.

In Figure 6 to 8, inclusive, I have shown a further modification wherein the hooks 14^b are provided on the outer face of the shanks with ears or lugs 14^c normally perpendicular thereto. When the hook is to be locked in its outer or projected position, the lugs are struck downwardly onto the face of the window frame to assume the positions shown in Figure 8.

It is to be noted particularly that by constructing the hook members so as to be capable of adjustment wholly within the outlines of the window frame all danger of injury to either the hooks or frames on the course of handling or transportation will be obviated. Further, by so constructing the parts, it becomes possible to pack a greater number of frames in a freight car or other vehicle since the necessity for providing spacing blocks or strips between window frames in order to prevent damage to either the hooks or frames is obviated.

Having thus described my said invention, what I claim and desire to secure by Letters Patent is:

1. A window frame including an attachment device having a portion adapted normally to occupy a position within the outline

of said frame, means for movably supporting said device upon said frame and to permit of the adjustment of said portion of the device to a position projecting outwardly beyond the outline of the frame, and means for securing said device to its projected position, substantially as specified.

2. A window frame including an attachment device having a portion adapted normally to occupy an inoperative position within the outline of said frame, means for pivotally supporting said device upon the frame and to permit of the adjustment of said portion of the device to an operative position projecting outwardly beyond the outline of the frame, and means for securing said device to its projected position, substantially as specified.

3. A window frame including an attachment device having a portion adapted normally to occupy a position within the outline of said frame, means for retaining said device against withdrawal from the frame, means for movably supporting said device upon the frame and to permit of the adjustment of said portion of the device to a position projecting outwardly beyond the outline of the frame, and means for securing said device to its projected position, substantially as specified.

4. A window frame having an aperture in the wall thereof, an attachment device having a portion adapted normally to occupy a position within the outline of said frame, and another portion pivotally and slidably mounted in said aperture, to permit of the adjustment of said portion of the device to a position projecting outwardly beyond the outline of the frame, and means for securing said device to its projected position, substantially as specified.

5. A window frame having an aperture in the wall thereof, having a portion adapted normally to occupy a position within the outline of said frame, means at the inner end of said device for preventing the withdrawal thereof from said frame, means for movably supporting said device upon the frame and to permit of the adjustment of said portion of the device to a position projecting angularly outwardly beyond the outline of the frame, and means for securing said device to its projected position, substantially as specified.

6. A window frame having an aperture in the side wall thereof, an attachment device comprising a shank having an outer end portion, an engageable member carried thereby, and retaining means at its inner end portion; said outer end portion being adapted normally to occupy a position within the outline of said frame, means for movably supporting said device intermediate its ends within said aperture to permit of the adjustment of said outer end portion to a position

projecting angularly-outwardly beyond the outline of said frame, and means for positively securing said device to its projected position, substantially as specified.

7. A window frame having a slot in the wall thereof, an attachment device having a head end adapted to project outwardly beyond the outer wall of said frame, and a shank end slidably and pivotally mounted in said slot whereby said head end may be swung inwardly behind said wall, means on said shank for preventing the same being withdrawn from said unit, and means whereby said head end may be locked in its outer operative position, substantially as specified.

8. A structural unit having a slot in a corner of the wall thereof, an attachment device having an outer head end adapted to project outwardly beyond the wall of said unit, and a shank end pivotally and slidably mounted in said slot whereby said head end may be swung inwardly behind said wall, and a part on the inner face of said shank and overlying the edges thereof; the overlying face of said part being adapted to contact the inner side of the wall of said unit to prevent the shank end from being withdrawn from said unit, and means whereby said device may be locked in outer operative position, substantially as specified.

9. A structural unit having a slot in the wall thereof, an attachment device having an outer head end adapted to project outwardly beyond the wall of said unit, and a shank end pivotally and slidably mounted in said slot whereby said head end may be swung inwardly behind said wall, means for preventing the withdrawal of said shank end from said slot comprising a part on the inner face thereof overlying the edges of said shank, said part being adapted to bear against the inner side of said wall adjacent the edges of said slot, a threaded aperture in the outer face of said shank end, and a screw adapted to engage said threaded aperture and having a head to bear upon the outer face of said wall adjacent said slot whereby the device may be secured to its outer operative position, substantially as specified.

10. A hollow window frame having a through slot in the wall thereof, an attachment device having an outer head portion adapted to project beyond the outer frame wall, an intermediate portion shaped to conform to and adapted to bear against the outer frame wall adjacent one end of the slot, and an inner shank portion pivotally and slidably mounted in the slot whereby said head end may be swung outwardly of said outer frame wall; said shank portion being shaped to conform to and adapted to bear against the inner frame wall adjacent another end of said slot, and means whereby the hook may be locked in its outer operative position, substantially as specified.

11. A device of the character described comprising a bell-crank member, a wedge-shaped arm tapering outwardly, a hook element projecting angularly from the wide outer end of said arm, a second flat arm substantially perpendicular to said first arm, and a part superimposed on said second arm and overlying the edges thereof, substantially as specified.

12. A hollow window frame including a plurality of side walls and slots therein, an attachment device comprising a substantially-flat base disposed wholly within said frame, members projecting outwardly from one edge of said base and through said slots, and a head at the outer end of each of said members; said base having a flat face portion conforming to and bearing against the inner side of one of the side walls of said frame, and said outwardly projecting member having a face portion disposed at right angles to the flat face of said base and conforming to and bearing against the outer side of a frame side wall adjoining said side wall first-named, substantially as specified.

Signed at the city of New York, in the county of New York, State of New York, this 25th day of April, one thousand nine hundred and thirty.

HARRY E. CAMPBELL.
